UNITED STATES PATENT OFFICE.

THOMAS F. Langley, of EAST KINGSTON, NEW HAMPSHIRE.

FAUCET.

SPECIFICATION forming part of Letters Patent No. 246,618, dated September 6, 1881.

Application filed April 2, 1881. (Model.)

To all whom it may concern:

Be it known that I, THOMAS F. Langley, of 5
East Kingston, in the county of Rockingham
and State of New Hampshire, have invented
an Improved Faucet; and I do hereby declare
that the following is a full and exact description
thereof, reference being had to the accompanying drawings, making part of this specification—

10 Figure 1 being a side view of the faucet; Fig.
2, a central longitudinal vertical section of the
same.

Like letters designate corresponding parts
in both figures.

15 The purpose of my invention is to make a
faucet which shall be simple, cheap, and com-
pact in construction, and effective, reliable, and
durable in action.

In construction the main part or body A,
20 bearing the spout a, has two internal flanges,
b c, one before and one back of the spout, with
a chamber, d, between, opening to the spout,
and easily formed therewith in casting the part.
The back flange, c, forms the seat for the clos-
25 ing-valve of the faucet, and the front flange, b,
forms both a packing-seat for the valve-stem
and the front wall of the water-passage. To
the rear end of this main part the tap part B
is screwed, and to the front end thereof a clos-
30 ing-cap, C, is screwed. The part B has formed
inside a guide-bearing, f, for the stem g of the
valve D, with water-passages through it around
the said stem; and the cap C forms another
guide-bearing for the valve-stem, which pro-
35 jects both forward and backward from the
valve, which is thereby kept properly centered,
and is allowed perfect freedom of movement
to and from its seat, which it closes against by
simple approach in the line of the axis of the
40 faucet-body; and the valve has a packing, h,
of leather, india-rubber, or other equivalent
material that is not subject to wear by friction,
and therefore will last a long time without re-
newing. The action of the water closes the
45 valve in the direct line of its motion, which is
the best possible arrangement. A light spring,
k, serves to assist in promptly closing the valve,
especially where the pressure of water is not
great. This spring is located back of the valve,
50 on its stem, and bears against the rear guide-
bearing, f, at one end. It is therefore always

immersed in water, and does not corrode as it
would if alternately wet and exposed to the
atmospheric air.

The cap C, in screwing into the front end of 55
the main part A, holds a stem-packing, i, be-
tween it and the packing-seat b, which, when
the valve is only partly open and the pressure
of the flowing water is comparatively little,
secures against leakage around the valve-stem, 60
while yet not causing much friction around the
stem; but when the valve is fully opened and
the pressure of water is great, this packing, if
it allows sufficient freedom of motion to the
valve-stem, cannot be relied on to prevent leak- 65
age around it. I therefore apply a head, l, to
the outer end of the valve-stem, with a pack-
ing, m, at its shoulder, which, when the valve
is opened, closes against the outer surfaces of
the cap C and makes all tight. This head also 70
serves as a stop to limit the back movement
of the valve, and the packing m additionally
serves as a cushion or buffer to prevent noise
when the stop reaches its limit. The head is
best secured to the end of the valve-stem by a 75
screw, n, so that it can be removed for renew-
ing the packing and other purposes.

The front cap, C, not only furnishes the bear-
ing for the outer end of the valve-stem, but it
bears the lever E or equivalent means by which 80
the valve is opened by simply pressing against
the outer end of the valve-stem or its head.
Instead of the lever, the valve may be opened
by a screw-wheel or other suitable means.

By the employment of the closing-cap C with 85
the packing back of it, in connection with the
valve-stem having a packing or valve-head, l,
on it, the faucet is rendered very compact and
of good shape, as well as tight, scarcely pro-
jecting forward of the spout a. The whole con- 90
struction, also, is simple, easy, and cheap. The
valve-spring k, being situated behind the valve
in the body of the faucet, also conduces to the
compactness of the construction.

In the construction herein represented, and 95
which is preferred, the lever E, which serves
to open the valve, also serves the purpose of
a wrench to screw on or off the cap C, to which
it is hinged.

What I claim as my invention, and desire to 100
secure by Letters Patent, is—

1. In a faucet, the double-stem valve D, op-

erating as described, its outer bearing being a cap, C, and packing-seat *b*, with a thin packing, *i*, between the same, substantially as and for the purpose herein specified.

5. 2. The packing-head *l* on the outer projecting end of the valve-stem, provided with a packing, *m*, at its shoulder, which closes against the outer surface of the faucet-cap C when the valve is opened, substantially as and for the purpose herein specified.

3. The combination, with the cap C, of the lever E, serving the double purpose of opening the valve and as a wrench to screw the cap on and off, substantially as herein specified.

The foregoing specification signed by me this 15
27th day of January, 1881.

THOMAS F. LANGLEY.
